OR D 12,982

DESIGN FOR THE ORNAMENTATION OF GLASSWARE.

Design No. 12,982, dated June 20, 1882.

UNITED STATES PATENT OFFICE.

PHILIP MACDONALD, OF CORNING, NEW YORK, ASSIGNOR TO THOMAS G. HAWKES, OF SAME PLACE.

DESIGN FOR THE ORNAMENTATION OF GLASSWARE.

SPECIFICATION forming part of Design No. 12,982, dated June 20, 1882.

Application filed March 21, 1882. Term of patent 7 years.

To all whom it may concern:

Be it known that I, PHILIP MACDONALD, a citizen of the United States of America, residing at Corning, in the county of Steuben and State of New York, have invented certain new and useful Improvements in Designs for Ornamentation of Glassware and Similar Articles; and I do hereby declare the following to be a full, clear, and exact description of the invention, such as will enable others skilled in the art to which it appertains to make and use the same.

The accompanying photograph, forming a part of this specification, is intended to show fully the nature of my design as applied to a glass plate or dish or similar articles. In this illustration it will be observed that the bottom of the plate is intersected by right lines *a b*, cut at predetermined distances entirely across the bottom, with intersecting diagonal lines *c d*, also cut at predetermined distances, running across the bottom of the plate, so that facets are cut or formed between the lines of irregular pyramidal shape, and so that the direction of these intersecting straight and intersecting diagonal lines leaves every third line of parallels *e* in one direction hexagonal in shape of its facets, with each facet having a broad face, and on this broad face is a star, as in the design accompanying this specification, or such other figure as may suit the fancy or taste of the artist; or it may be left plain, if so desired. Substantially the same arrangement of lines is employed in the ornamentation of circular surfaces. Lines *a'* run parallel with the periphery and with each other, according to the dimensions of the surface to be ornamented, and intersecting these are lines *b'*, diverging regularly from the central point to the circumference, with scrolled lines *c'* intersecting both, which leaves the third line of facets, *d'*, hexagonal, as heretofore stated, and with broadened faces, and on these faces is a star or other device, as heretofore stated.

The leading feature of my design consists in disposing the lines opposing or intersecting

each other so that the third parallel of facets in one direction is hexagonal with broad faces, and on these broad faces a figure is cut to suit the taste of the artist.

It is obvious that any figure may be cut on the hexagonal or "hob-nail." In other respects the figures are always the same.

What I claim is—

1. The design for ornamentation of glass or similar wares herein shown and described, the same consisting of continuous intersecting right lines and intersecting diagonal lines, forming pyramidal facets with regularly-recurring hexagonal facets with broadened faces. 55

2. The design for ornamentation of glass and similar wares herein shown and described, the same consisting of intersecting right lines and intersecting diagonal lines so disposed that every third parallel of facets shall be hexagonal in shape, with broadened faces and with an ornament on said broadened faces. 60

3. The design for ornamentation of glass and similar wares herein shown and described, the same consisting of lines parallel to the periphery and with each other, with intersecting straight lines diverging from the central point and intersecting scrolled lines, all so disposed that every third line of facets in one direction shall be hexagonal and formed with a broad face. 75

4. The design for ornamentation of glass and similar wares herein shown and described, the same consisting of lines parallel to the periphery and with each other, with intersecting straight lines diverging from the central point and intersecting scrolled lines, all so disposed that every third line of facets in one direction shall be hexagonal and formed with a broad face with an ornament on said broadened face. 85

In testimony whereof I affix my signature in presence of two witnesses.

PHILIP MACDONALD.

Witnesses:

QUINCY W. WELLINGTON,
GEO. T. SPENCER.
